(57) **CLAIM**

The ornamental design for a cutting board, as shown and described.

DESCRIPTION

FIG. 1 is a perspective view of a cutting board according to the present invention.

FIG. 2 is a front elevation view of the cutting board illustrated in FIG. 1.

FIG. 3 is a rear elevation view of the cutting board illustrated in FIG. 1.

FIG. 4 is a side elevation view of the cutting board illustrated in FIG. 1.

FIG. 5 is another side elevation view of the cutting board illustrated in FIG. 1.

FIG. 6 is a top plan view of the cutting board illustrated in FIG. 1.

FIG. 7 is a bottom plan view of the cutting board illustrated in FIG. 1.

FIG. 8 is a sectional view of the cutting board illustrated in FIG. 1 and taken through line 8-8 in FIG. 6.

FIG. 9 is a sectional view of the cutting board illustrated in FIG. 1 and taken through line 9-9 in FIG. 6.

FIG. 10 is a sectional view of the cutting board illustrated in FIG. 1 and taken through line 10-10 in FIG. 6; and,

FIG. 11 is a sectional view of the cutting board illustrated in FIG. 1 and taken through line 11-11 in FIG. 6.

The broken away symbols in the drawings indicate the appearance of any portion of the article between the break lines forms no part of the claimed design.
